UNITED STATES PATENT OFFICE.

JOHN G. KING, OF CHARLOTTE, NORTH CAROLINA.

PICK-FINDING DEVICE.

No. 839,485.

Specification of Letters Patent.

Patented Dec. 25, 1906.

Application filed December 19, 1905. Serial No. 292,474.

To all whom it may concern:

Be it known that I, JOHN G. KING, a citizen of the United States, residing at Charlotte, in the county of Mecklenburg and State of North Carolina, have invented certain new and useful Improvements in Pick-Finding Devices; and I do hereby declare the following to be a full, clear, and exact description of the invention, such as will enable others skilled in the art to which it appertains to make and use the same.

The invention relates to a pick-finding device used in connection with the stopping mechanism of a loom; and the object of the device is to control the belt-shipper handle when the loom attempts to stop or change the filling automatically until the loom is in a preferred position, so as to avoid mispicks.

In the drawings, Figure 1 is an end view of the pick-finding mechanism, showing also portions of the loom. Fig. 2 is a front view of the same. Fig. 3 is a sectional plan view taken on the line $\alpha\alpha$ in Fig. 2.

A is a portion of the frame of the loom, and A' is the lay which supports the shuttle, which is forced from one side of the loom to the other.

B is the lay-sword, which is mounted on a shaft B' and which is oscillated crosswise of the lay by any approved driving mechanism.

C is the filling-fork, which is pivoted in a filling-fork slide or slip b, which is slidable crosswise of the lay in a guide b'.

D is the filling-fork lever, which is pivoted to the frame A by a pin d. One end of this lever engages with the rear end projection c of the filling-fork, and its other end portion is operated by a cam D', which is revolved continuously by any approved driving mechanism. When the filling is absent, the lay-sword fails to tip the filling-fork on its pivot, and the lever D then engages with the part c and moves the filling-fork and its slip backward crosswise of the lay.

E is the controlling or stopping lever of the loom. This lever is preferably a spring-lever having its lower end secured to the loom-frame, and it is normally held in position by a catch. When the filling-fork slip is moved back, it operates a trip e, which releases the spring-stopping lever from its catch. This stopping-lever is provided with or connected to a belt-shipper E' of any approved construction, and when it is released from its retaining-catch it normally ships the driving-belt onto the loose pulley and stops the loom.

All the above-mentioned parts are of ordinary approved construction, such as commonly in use on looms.

In order to prevent the loom from stopping suddenly and to constrain it to stop in a preferred and prearranged position, a novel pick-finding device is used, as hereinafter described.

F is a lever which is pivoted to the frame A by a pin f. The lower end portion of this lever is provided with a slot f', which engages with a pin F' on a bracket secured to the lay-sword B, so that the lever is oscillated by the lay-sword. The upper end portion of the lever F has a hook-pawl G pivoted to it by a pin g.

H is a ratchet-toothed wheel which is journaled on a pin h, which projects from the frame A, and h' is a pivoted check-pawl which prevents the said ratchet-wheel from being revolved backward. A pin 3 is secured to one of the said pawls and holds the other said pawl at a prearranged distance from it. A dog g' is pivoted on the pin h and normally supports both pawls G and h' so that they are normally out of engagement with the teeth of the ratchet-wheel.

I is a supplemental retaining-catch for the belt-shipper lever E. This catch I has a hooked outer end i, which engages with the lever E, and it is pivoted on a vertical pin i', which projects from a bracket I', which is secured to the frame A. The inner end portion of the catch I projects under the ratchet-toothed wheel H and is operatively connected with the lower end portion of the dog g'.

J is a spring coiled about the pin h and connected with the ratchet-toothed wheel and the frame, so that the ratchet-wheel is revolved backward when the check-pawl h' is released. A stop j projects from the ratchet-toothed wheel and engages with the frame, so that the spring J cannot revolve the ratchet-toothed wheel too far in a backward direction.

A spring retaining device is provided for holding the catch I in its extreme positions. This retaining device preferably consists of two levers K and K', which are pivoted to the frame A by pins k and k', respectively. The adjacent end portions of these two levers are connected by a pin L, and M is a spring secured to the opposite end portions of the said levers. The upper lever K is provided with a projection m, which engages with the catch I, and the said device holds

the catch in either of its extreme positions and prevents it from being displaced accidentally or prematurely. Stop-pins 4 are provided on the frame A for limiting the movements of the levers K and K'.

5 N is a trip-lever which is secured on a shaft n, which is journaled in the frame. The lower end portion of this lever bears against one side of the inner end portion of the catch I. N' is an arm which is also secured to the shaft n and which is arranged in the rearward path of the filling-fork slip b.

10 P is a pin which projects radially from the ratchet-toothed wheel, and p is a series of 15 holes in the said wheel. The pin P may be placed in engagement with any one of the holes p, and it is arranged in the path of the catch I.

15 The operation of the pick-finding device is 20 as follows: When the filling is absent and the filling-fork lever therefore moves the filling-fork slip backward, the said slip strikes the arm N' and causes the lever N to move the catch I into the path of the stopping-lever E.

25 The spring M causes the catch I to move suddenly and retains it in position. This movement of the catch I turns the dog g' on its pivot and allows the two pawls G and h' to engage with the teeth of the ratchet-wheel H.

30 The ratchet-wheel is then revolved intermittently from the lay-sword by means of the lever and hook-pawl and against the tension of the spring J until the pin P strikes the catch I and moves it out of engagement with

35 the stopping-lever E. The loom is stopped automatically when the lever E is released, and the moment of its release is determined by the position of the pin P. The catch I holds the stopping-lever until the loom has

40 made any desired or prearranged number of picks after the filling is exhausted. A loom provided with this device and operating on any kind of twills, ranging from three to twelve harness, can be made to find the pick

45 before it stops after the filling gives out, and the loom will stop with the correct shed open and ready to receive the new filling without any trouble to the operator. When the catch I releases the controlling or stopping 50 lever E, it raises the pawls out of engagement with the ratchet-toothed wheel, and the said wheel is restored to its original position by the spring J. As the catch I is normally out of engagement with the stopping-lever, the 55 said stopping-lever can be operated by hand as often as desired in the ordinary manner.

This device can be applied to various makes of loom without altering or interfering with the working parts of the same, and it can 60 also be applied to what is known as an "automatic" loom by making the catch I engage with the changer-lever instead of the belt-shifter lever.

What I claim is—

65 1. The combination, with a loom provided

with a controlling-lever, a lay-sword, a filling-fork slide having a filling-fork, and means for actuating the said parts; of a pick-finding device comprising a catch for holding the said controlling-lever, lever mechanism for moving the said catch into engagement with the said lever when the said filling-fork slide is retracted, and tappet mechanism for subsequently releasing the said lever operatively connected with the said lay-sword. 7

2. The combination, with a loom provided with a controlling-lever, a lay-sword, a filling-fork slide having a filling-fork, and means for actuating the said parts; of a pick-finding device comprising a catch for holding the said controlling-lever, lever mechanism for moving the said catch into engagement with the said lever when the filling-fork slide is retracted, a wheel provided with an adjustable tappet for releasing the said lever from the said catch, driving devices for revolving the said wheel from the said lay-sword, and means for placing the said wheel into and out of engagement with the said driving devices connected to the said catch. 8

3. In a pick-finding device, the combination, with the controlling-lever and the filling-fork slide of a loom; of a pivoted catch for engaging the said controlling-lever, and trip mechanism arranged in the path of the said filling-fork slide and operating to place the said catch in engagement with the said lever when the said slide is retracted.

4. In a pick-finding device, the combination, with the controlling-lever and the filling-fork slide of a loom; of a pivoted catch for engaging the said controlling-lever, a rock-shaft, an arm secured on the said rock-shaft and arranged in the path of the said filling-fork slide, and a trip-lever secured on the said rock-shaft and operating to place the said catch in engagement with the said lever when the said slide is retracted.

5. In a pick-finding device, the combination, with the controlling-lever and the lay-sword of a loom; of a pivoted operating-lever connected with the said lay-sword, a revolvable ratchet-toothed wheel, a pawl for revolving the said wheel from the said operating-lever, a dog normally holding the said pawl out of engagement with the said wheel, a catch for engaging with the said controlling-lever operatively connected with the said dog and holding it in its normal position until the said catch is moved into the path of the said controlling-lever, and a tappet for subsequently moving the said catch out of engagement with the said controlling-lever, said tappet being operated by the said ratchet-wheel.

6. In a pick-finding device, the combination, with the controlling-lever and the filling-fork slide of a loom; of a pivoted catch for engaging the said controlling-lever, two pivoted levers having their adjacent end por-

tions pivotally connected together and one of the said levers being operatively connected with the said catch, a spring arranged between the opposite end portions of the said levers and operating to retain the said catch in its extreme positions, and trip mechanism arranged in the path of the said filling-fork slide and engaging with the said catch.

7. In a pick-finding device, the combination, with the controlling-lever and the lay-sword of a loom; of a pivoted operating-lever connected with the said lay-sword, a revolvable ratchet-toothed wheel, a pawl for revolving the said wheel from the said operating-lever, a pivoted stop-pawl, a dog which normally holds both the said pawls out of engagement with the said wheel, a catch for engaging the said controlling-lever operatively connected with the said dog, and a tappet operated by the said ratchet-toothed wheel for moving the said catch out of engagement with the said controlling-lever.

8. In a pick-finding device, the combination, with the controlling-lever and the lay-sword of a loom; of a pivoted operating-lever connected with the said lay-sword, a revolvable ratchet-toothed wheel provided with a series of holes, a pawl for revolving the said

wheel from the said operating-lever, a catch for engaging the said controlling-lever, a dog 30 operated by the said catch and normally holding the said pawl out of engagement with the said wheel, and a trip-pin engaging with one of the said holes and operating to disengage the said catch from the said controlling- 35 lever and to disengage the said pawl from the said wheel.

9. In a pick-finding device, the combination, with the controlling-lever of a loom, a revoluble wheel, and a return-spring connect- 40 ed thereto; of driving mechanism for revolving the said wheel against the tension of the said spring, a catch for engaging the said controlling-lever, a trip-pin projecting from the said wheel and engaging with the said catch, 45 and means for disengaging the said driving mechanism from the said wheel operated by the said catch upon the release therefrom of the said controlling-lever.

In testimony whereof I have affixed my 50 signature in the presence of two witnesses.

JOHN G. KING.
